UNITED STATES PATENT OFFICE.

JAMES L. McQUARRIE, OF NEW YORK, N. Y., ASSIGNOR TO WESTERN ELECTRIC COMPANY, OF CHICAGO, ILLINOIS, A CORPORATION OF ILLINOIS.

SELECTOR FOR AUTOMATIC TELEPHONE-EXCHANGES.

No. 826,350.

Specification of Letters Patent.

Patented July 17, 1906.

Application filed October 16, 1905. Serial No. 223,002.

To all whom it may concern:

Be it known that I, JAMES L. McQUARRIE, a citizen of the United States, residing at New York, in the county of New York and State of New York, have invented a certain new and useful Improvement in Selectors for Automatic Telephone-Exchanges, of which the following is a full, clear, concise, and exact description.

10 My invention relates to a selector for an automatic exchange system; and its object is to provide an improved arrangement of the electromagnets and their armatures and the pawls actuated thereby to control the movement of the selector-arm.

15 In my invention the electromagnets are arranged on the under side of the plate which carries the trailer-arm, and the cores of said electromagnets extend through openings in the plate to the opposite side. My invention thus provides a compact arrangement of the various parts of the selector, all suitably mounted upon a single plate.

20 I will describe my invention in detail by reference to the accompanying drawings, in which—

Figure 1 is a plan view of the selector mechanism which is provided for each line at the central office. Fig. 2 is a side elevation of the selector mechanism, the supporting-frame carrying the switch-contacts being in cross-section. Fig. 3 is a section on line 3 of Fig. 1, and Fig. 4 is a section on line 44 of Fig. 1.

25 The same letters of reference are used to designate the same parts wherever they are shown.

30 Each selector is provided, as usual, with circular rows of terminal pieces or contacts a' a^2 , mounted upon the selector-frame a . Each selector is also provided with an arm b , fastened radially upon a ratchet-wheel b^3 , which is mounted in a suitable frame, so as to rotate above the supporting-plate e . Said 35 ratchet-wheel is arranged to be rotated by a stepping magnet c and to be held in its advanced position by a retaining-magnet d . The selector-arm b , which is advanced by the rotation of the ratchet-wheel, carries two 40 contact-brushes b' b^2 , adapted to trail over the pairs of stationary line-terminals a' a^2 , arranged in a circle about its axis.

The electromagnets c and d are disposed

beneath the plate e , with their cores c' d' extending through openings in said plates and secured by screws f' g' to the legs of the brackets f g , respectively, said brackets being secured by screws or in any other suitable manner above the plate e . The portions of the cores c' d' projecting through the plate are cut away at c^2 d^2 , as shown in Figs. 4 and 3, respectively, to form a flat surface adjacent to the legs of the brackets f and g in order that said cores may be firmly held in position against their supports.

45 The yoke pieces c^3 d^3 of the electromagnets have adjustable screws c^4 d^4 extending through them, forming bearings for the lower end of the rods c^5 d^5 , respectively. The upper ends of said rods have enlarged slotted heads c^6 d^6 , respectively, which project through openings in the plate e and form supports for the armatures c' d' of the electromagnets. Pins c^7 d^7 extend from said armatures through nuts secured in openings in the brackets f and g . The armatures c' d' are thus pivotally mounted between the projecting core-pieces c' c^2 and d' d^2 , respectively.

50 The armature c' of the stepping magnet c carries a pawl c^8 , which when said armature is in its normal unattracted position is held by the pin h out of engagement with the teeth of the ratchet-wheel b^3 . When the armature is attracted, the pawl c^8 is released from the pin h and is drawn by a spring into engagement with the teeth of the ratchet-wheel to advance the same one step for each 55 impulse of current through the stepping-magnet.

55 The armature d' of the retaining-magnet d controls a pawl d^8 , normally holding the same out of engagement with the ratchet-wheel b^3 , as shown in Fig. 1. When the armature d' is in its attracted position, the pawl d^8 is released and holds the ratchet-wheel in its advanced position.

60 When a subscriber operates his interrupter in the usual manner in making a call, the stepping magnet c is caused to intermittently attract its armature c' and so to advance the selector-arm step by step. The selector-arm is held in its advanced position by the retaining-pawl d^8 , controlled by the retaining-magnet d , which is made sluggish, so as not to follow the pulsations of the current, but to keep its armature steadily at

tracted. When the magnet d is deenergized, its armature d^1 is drawn back by a spring and withdraws the pawl d^0 from engagement with the ratchet-wheel. Said wheel and the arm 5 b are then returned to their initial position in the usual manner by a coiled spring s . (Shown in Fig. 2.)

I claim—

1. In a selector for an automatic telephone-exchange, the combination with a ratchet carrying a selector-arm, of a plate upon which said ratchet is mounted, an electromagnet for actuating said ratchet, said magnet being disposed upon the rear of the plate with its core-piece projecting through an opening in the same, and a bracket mounted upon the front of the plate and providing a support for said core-piece and magnet.
2. In a selector for an automatic telephone-exchange, the combination with a ratchet carrying a selector-arm, of a plate upon which said ratchet is mounted, an electromagnet disposed upon the rear of said plate and having a core-piece projecting through an opening in the same, a bracket mounted upon the front of the plate and providing a support for said core-piece and magnet, an armature for said magnet pivotally secured to said bracket, and means controlled by said 30 armature for actuating said ratchet.
3. In a selector for an automatic exchange, the combination with a ratchet carrying a selector-arm, of a plate upon which said ratchet is mounted, an electromagnet for actuating said ratchet, said magnet being disposed upon the rear of the plate with its core-pieces projecting through openings in the same, a bracket mounted upon the front of the plate to which said core-pieces are secured, a rod 40 having a pivotal bearing in the yoke of the electromagnet and extending through an opening in the plate, an armature secured to said rod above the plate and between the poles of the magnet, and mechanism actuated by said armature for controlling the movement of said ratchet.
4. The combination with a selector-frame provided with a series of circularly-arranged contact-terminals, of a plate secured to said 50 frame within the circle of said terminals, a ratchet-wheel rotatably mounted above said plate, a selector-arm carried by said wheel

and provided with contact-brushes adapted to trail over said terminals, two electromagnets disposed upon the rear of the plate, each 55 having its core-pieces extending through openings in said plate, brackets mounted upon the front of the plate to which said core-pieces are secured, an armature for each magnet pivoted to said brackets between the 60 opposite poles of the magnet, and pawls controlled by said armatures for advancing the ratchet-wheel and for holding said wheel in its advanced position.

5. In an automatic telephone-exchange 65 system, the combination with a selector-frame provided with a series of circularly-arranged line-terminals, of a plate secured to said frame within the circle of said terminals, a ratchet-wheel rotatably mounted above 70 said plate, a selector-arm radially secured to said wheel and provided with contact-brushes adapted to trail over said terminals, electromagnets disposed upon the bottom of the plate having core-pieces extending through 75 openings in the same, a bracket for each magnet mounted upon the top of the plate and to which said core-pieces are secured, rods pivotally mounted in adjustable bearings carried by the yokes of the electromagnets, an enlarged slotted head for each rod extending through an opening in the plate, an armature for each magnet secured within 80 said slotted head and provided with a pin extending through an opening in the corresponding bracket, and means actuated by said armatures for controlling the movement of said ratchet-wheel and selector-arm.

6. In a selector for an automatic telephone-exchange, the combination with a ratchet 90 carrying a selector-arm, of a plate upon which said ratchet is mounted, an electromagnet disposed upon the rear of the plate with its core-piece projecting through an opening in the same, an armature pivoted 95 above the plate, and means controlled by the movement of said armature to control the movement of said ratchet.

In witness whereof I hereunto subscribe my name this 21st day of August, A. D. 1905.

JAMES L. McQUARRIE.
